CONTROL MECHANISM.

Application filed July 30, 1925. Serial No. 47,159.

The present invention relates to control mechanisms which may be adaptable for various purposes and in a variety of ways. The particular object of the invention, however, 5 is to provide a mechanism for controlling the operation of theatre curtains and to provide a simple, easily controlled and operated device by which the movement of the curtain can be governed. The apparatus shown herein 10 is constructed so that with a single, one-way switch, the curtain can be stopped, started, reversed or caused to stop in its movement and then continue in the same direction.

It is apparent that the principles of the 15 invention may be embodied in other forms than that shown and the scope of the invention is not limited to exact conformity with the details illustrated and described, and it is also obvious that the apparatus may be 20 utilized for other purposes and is not confined to curtain operation.

In the drawings in which is shown one embodiment of the invention as applied particularly to theatre curtain control:

25 Figure 1 is a plan view of the improved apparatus;
 Figure 2 is an end view thereof;
 Figure 3 is a side view;
 Figure 4 is a section on the line 4—4 of Figure 2;
 Figure 5 is an enlarged view of the control drum operating mechanism;
 Figure 6 is a detailed view of the drum rotating device;
 35 Figure 7 is a detail of the pawl;
 Figure 8 is a plan view of the control drum;
 Figure 9 is an elevation thereof;
 Figure 10 is a diagrammatic view of the wiring device;
 40 Figures 11 and 12 are front and side views, respectively, of an alternative method of securing the curtain; and
 Figures 13 to 16 are details thereof.

The control device is mounted upon a substantially L-shaped base or platform 1, to which is secured the motor 2, which, through the flexible coupling 3, drives the worm 4. The worm and worm gear 5 are supported within a housing 6, the gear being secured to 45 a driving shaft 7 mounted in bearings 20 and 21 upon the housing. To the shaft 7 is secured a disk or plate 8, facing which is located a second plate 9, freely rotatable on the shaft, between which plates is located a series of 55 balls 10, seated within sockets upon the plates 8 and 9. To the plate 9 is secured a pulley 11

against which bears a coil spring 12 confined at its outer end by nuts 13 on the end of the shaft, and adjustable to regulate the pressure of the spring. By the arrangement described, 60 provision is made for the release of the pulley 11 from the shaft should the curtain stick at any point in its travel, the spring being adjusted so that rotation is normally transmitted through the ball clutch 8—9—10, but 65 in the case of an overload the ball clutch will permit the shaft to turn without rotating the pulley 11.

The curtain rope 16 passes over the pulley 11, being crossed as shown in Figure 2 and 70 received within grooves upon a freely rotating pulley 17 and thence to the curtain. The pulley 17 is carried upon the end of a stub-shaft 18 located on the end of an arm 19 which is passed over the housing 21 to which it is 75 adjustably secured in any desired angular position by a set screw 22, this arrangement permitting a certain adjustment of the arm 19 to accommodate varying theatre buildings.

The motor 2 is stopped and started by 80 means of a rotating control drum to be described, and is also automatically stopped at the upper and lower limits of its movement.

The rotating control drum referred to is indicated by the numeral 25, being carried 85 upon a shaft 26 mounted in an inverted U-shaped frame 27 and is designed to control the motor 2 by any suitable wiring, one form of which is shown in Figure 10. The motor 2 is a reversible one and is designed to be rotated in alternate directions as the rotating drum 25 is turned to afford the required contacts.

In the form shown, the drum 25, which is made of an insulating material, carries upon 95 its surface two oppositely positioned L-shaped contact rails 30, the long and short arms of which are placed in opposition, spaced 180° about the drum and connected across the ends of the drum. Insulating rings or walls 31 separate the long end of one rail and the short end of the other and additional rings 32 are provided at the ends of the drum. A series of spring brushes or contact fingers 33 are secured to the bottom of the pan 34 in which 100 the mechanism is located.

The drum is arranged to be rotated through 90° at a step so that the spaces between the rails 30 afford dead points about the drum. When, however, the contacts rest upon the 110 rails the motor 2 is rotated in either direction depending upon the position of the drum,

wiring to accomplish the result being shown in Figure 10.

The drum is rotated through 90° by means of a vertically arranged solenoid 40 which is 5 adapted to be energized by a one-way switch 41. Only one switch is shown, but it will be evident that there are to be several control stations in which switches may be located and from which the curtain may be operated. The 10 switch 41 is preferably a snap switch and when it is closed the solenoid 40 is energized, drawing up the core 42 which is arranged to strike against a felt pad or cushion 42a in the upper end of the solenoid. The weight of the 15 core causes it to drop after the solenoid is deenergized.

At its lower end the core 42 carries a ball and socket or other universal joint 43, to which is attached one end of the link 44, the 20 other end being attached to a lever 45 rotatably mounted upon the shaft 26 at one end of the drum. A pawl 46 is carried upon the lever 45 and engages a ratchet 47 secured to the drum. The stroke of the lever 45 is sufficient 25 to rotate the drum through one-quarter of a turn, but in order to insure the stopping of the drum in correct position, a squared plate 48 is carried upon the shaft 26, the plate being received between parallel arms 50 which 30 are urged together by a coil spring 51 passing over a pin 52 located across the ends of the arms, the construction assuring accurate positioning of the drum.

It will thus be seen that by closing the single 35 switch 41, the operator of the curtain can energize the solenoid and cause a quarter turn in the control drum, causing the motor 2 to stop or start and thereby controlling the movement of the curtain. Should, for example, the curtain be moving downwardly and it 40 be desired to stop it, a momentary closing of the switch will cause the drum to revolve until the brushes 33 rest upon the dead position of the drum. If the curtain is then to be raised, closing 45 of the switch will bring the rails in contact with the brushes 33 and the motor will revolve in the opposite direction. If, however, the curtain is to continue its downward movement, three short operations of the 50 switch will bring the drum around to cause the motor to rotate in the required direction.

The mechanism described is wholly under the control of the operator, and, in addition, a positive stopping device is provided by 55 means of which the motor is stopped automatically when the curtain is at its upper and lower limits. Upon the shaft 7 within the housing 6 is located a worm 60 which drives a spiral gear 61 which rotates a shaft 62 projecting outwardly from the housing and carrying two adjustable dogs 63 which are designed to wipe against curved surfaces 64 upon opposite sides of a trip lever 65 pivoted upon the housing.

65 The lever 65 is connected to a link 66 which

rides at its other end upon a pin 58 in a lever 68 pivoted upon the frame 27. A spring 67 is located between a collar 59 and a washer 57 on the link 66. The lower end of the lever 68 is designed to contact a pawl 69 which is 70 loosely mounted on the end of the shaft 26 adjacent the plate 48. A light coil spring 70 is secured at one end to a pin 71 on the pawl 69 and at the other to a pin 72 on the plate 48. As the curtain is raised or lowered, the shaft 75 62 is rotated and the dogs 63 contact the curved surfaces 64 and rocking the lever 65 and moving the link 66 until the compression of the spring 67 snaps the pawl over and brings the drum to a "dead" position, at 80 which time the dogs pass off the surfaces 64 and the parts are restored to their idle position. One dog is for stopping the upward movement of the curtain and the other for stopping its downward movement and the 85 adjustments of the dogs are regulated by the distance the curtain is required to travel.

In the form of the device shown in Figures 1 ad 2, the curtain is attached directly to the 90 rope 16. In Figures 11 to 16 incl., the curtain is positively operated, the pulley 11 being replaced by a sprocket 80. A chain 81 passes over the sprocket and over a sprocket 82 supported in the hanger 83. The ropes 84 for the curtain are secured to opposite runs of the 95 chain by means of clamps 85 and pass over pulleys 86 in the hanger 83.

What is claimed is:

1. In a mechanism for operating curtains or for similar purposes, comprising a motor, 100 a rotating shaft operated by the motor, an adjustable dog upon the shaft, lever mechanism within the path of the dog, a rotating control drum, and mechanism for rotating said drum step by step mechanically connected to and operated by said lever.

2. In a mechanism for operating curtains or for similar purposes, comprising a motor, a rotating shaft operated by the motor, an adjustable dog upon the shaft, lever mechanism within the path of the dog, a rotating control drum, mechanism for rotating said drum step by step mechanically connected to and operated by said lever, and a manually 110 controlled circuit including a solenoid and a ratchet mechanism for said drum operated thereby.

3. In a device of the character described, a rotating control drum having separated contact points, brushes bearing against the surface of the drum, mechanism for rotating said drum to bring the brushes in contact with the points and between said points alternately, a second mechanism operable independently of the first-named mechanism to rotate said drum to place the brushes between the contact points only, a snap switch for controlling the first said mechanism, stops for actuating the second-named mechanism and means for actuating the stops.

4. In a device of the character described, a rotating control drum having separated contact points, brushes bearing against the surface of the drum, ratchet mechanism for rotating said drum to bring the brushes in contact with the points and between said points alternately, a second mechanism operable independently of the first-named mechanism to rotate said drum to place the brushes between the contact points only, manually controlled means for operating the ratchet mechanism, and automatically controlled means for operating the second mechanism.

5. A curtain operating mechanism comprising a rotary contact drum for controlling the movement of the curtain, means to rotate the drum step by step, a plate having flattened sides attached to the drum, and spring actuated arms bearing against the sides of the plate.

6. A curtain operating mechanism comprising a reversible motor, a rotary control drum therefor, sets of brushes connected to the motor and bearing against the surface of the drum, and contact plates on the drum having long and short arms placed in reversed relation.

7. A curtain operating mechanism comprising a reversible motor, a rotary control drum therefor, sets of brushes connected to the motor and bearing against the surface of the drum, and contact plates each having long and short arms placed at different points about the drum and said long and short arms being connected together across the drum, the plates being placed in reverse relation upon the drum.

8. A theater curtain operating mechanism, having provisions for starting and stopping the curtain and moving it in either direction at the control of the operator, said mecha-

nism comprising the combination of a reversible motor, a curtain moving mechanism actuated by said motor, and control mechanism for said motor comprising a rotatable drum having separated forward and reverse contacts electrically connected to said motor and separate mechanisms to rotate said drum positively step by step comprising (1) a solenoid, a manually operated switch to energize the solenoid, a one step mechanical feed device connected to the solenoid and movable thereby and (2) a mechanical device for rotating the drum operated by the curtain at the limits of its movement.

9. In control mechanism for movable curtains, particularly theater curtains, comprising the combination of a reversible electric motor, curtain moving mechanism operated by the motor, a rotatable drum switch having forward and reverse contact separated by non-conducting points, and means to rotate said drum positively step by step comprising two mechanical feed devices, an electrically controlled actuating mechanism for one of said feed devices, stops for actuating the second feed device at the limits of movement of the curtain and a single contact switch for operating the electrically controlled actuating mechanism.

10. In a control mechanism for movable curtains, comprising a reversible motor, a rotatable control drum having forward and reverse contacts separated by non-conducting points, a ratchet operable to turn the drum when moved in one direction, a magnetic device to move the ratchet and thereby turn the drum step by step, a manually operated switch to energize the magnetic device, and a second device actuated by the curtain at the limits of its movement to rotate the drum.

EARL J. VALLEN.
